APPARATUS FOR FORMING CONCRETE FLOORS

Henry W. Roos, Cincinnati, Ohio

Application January 17, 1930, Serial No. 421,488

2 Claims. (Cl. 25—131.5)

This invention relates to apparatus for forming concrete floors, and particularly to apparatus for forming concrete beams and girders for reinforcing the floor.

5 The principal object of the invention is to provide improved apparatus for constructing beam and girder forms for concrete floors which are light in weight, cheaply constructed, and which are more quickly assembled than forms heretofore used.

10 Another object of the invention is the provision of special beam and girder forms which may be readily and quickly assembled in the floor mold on temporary supports.

15 A further object of the invention is to provide a form for molding beams or girders which may be readily constructed of separate parts and assembled in the floor mold as a unit on temporary supports.

20 Still another object of the invention is the provision of forms for molding beams or girders which are adjustable to provide for the formation of beams or girders of different depths for the construction of floors adapted to carry different loads.

25 Another object of the invention is the construction of floor forms including beam and girder forms which can be readily assembled on temporary supports or shores to form a floor mold, and which can be readily removed from beneath the concrete floor before the concrete has entirely set and without removing the shores, which are thus left to support the concrete.

To these and other ends, the invention consists in the construction and arrangement of parts that will appear from the following description when read in conjunction with the accompanying drawings, the novel features being pointed out in the claims following the specification.

30 In the drawings:

Figure 1 is a fragmentary plan view of a floor mold constructed according to one embodiment of the invention;

Figure 2 is a vertical section of the same taken substantially on line 2—2 of Figure 1, and looking in the direction of the arrows at said line;

Figure 3 is a section on line 3—3 of Figure 1, looking in the direction of the arrows at said line;

Figure 4 is an inverted plan view, the temporary supports or shores being sectioned away substantially on line 4—4 of Figure 2;

Figure 5 is a fragmentary plan view showing a beam mold mounted in a slightly different manner;

Figure 6 is a vertical section taken substantial-

ly on line 6—6 of Figure 5 and looking in the direction of the arrows at said line;

Figure 7 is an inverted perspective view of disassembled parts shown in Figure 5.

Referring to the drawings, in which similar reference numerals refer to the same parts in all the figures, Figure 1 shows a floor mold formed by assembling floor forms 1 of usual or well known construction, rectangular or square in shape and mounted on temporary supports or shores 2, see Figure 2, having brackets 3 adapted to releasably engage adjacent forms at or near their corners. The brackets 3 are provided with outwardly inclined engaging members adapted to cam adjacent forms into close engagement with each other. The forms 1 are assembled in aligned rows, both longitudinally and transversely, and forms adapted to mold a girder such as shown at 4 may be mounted between two transverse rows of forms 1, and forms adapted to mold a beam such as shown at 5 may be mounted between two longitudinal rows of forms 1. At the outside of the floor at 6 is shown a mold for an outside beam or lintel, and at 7, where the girder 4 intersects the beam or lintel 6, is shown a permanent support or vertical column.

The forms for the beams and girders are substantially similar in construction, and only one will be described in detail. Each of said forms comprises vertical side walls 10 and 11 preferably constructed of sheet material, and a bottom wall 12 secured between and connecting them. The bottom wall has downwardly projecting flanges 13 at its sides which engage the inner walls of the side members 10 and 11 and to which it is secured by any suitable means, as by the bolts 14. Secured to the outer walls of the side members and flush with their upper edges are laterally extending forms 15 having depending marginal flanges 16 whereby they may be secured to the side members 10 and 11 by means of bolts or other suitable means. The flanges 16 also serve to reinforce the forms 15 which may be further reinforced by transversely extending bars 17 welded to the bottom thereof, see Figure 10. The forms 15 are roughly T-shaped in outline, although other forms are sometimes required to fill in the mold for a floor.

The forms 15 are of a length substantially equal to the sides of the forms 1, and have openings 50 at their corners adapted to fit around the tops 16 of the temporary supports or shores 2, having the brackets 3 which releasably engage the corner flanges of the forms and support them with their upper surfaces in the plane of the forms 1. 55

By this construction, the beam or girder forms may be assembled in sections and the sections mounted as units on the temporary supports in the gaps provided therefor between the rows of 5 standard forms 1.

Since the beams and girders to be formed are not uniformly of the same vertical depth, it is desirable to provide beam or girder forms with which beams or girders of various depths may 10 be formed. For this purpose, the sides 10 and 11 of the beam forms may be provided with aligned openings 22, see Figures 2 and 6, in a plurality of horizontal planes, which the bolts 14 may engage to secure the bottom wall 12 in any one of 15 several horizontal planes between the side walls 10 and 11.

If desired, the lateral edges of the bottom wall may be reinforced by means of angular strips 13a. The side and bottom walls may also be reinforced 20 by means of reinforcing strips welded thereto at suitable intervals, as shown in Figure 4. A reinforcing strip may be provided at each of the ends of the side walls having an outwardly projecting flange 25. The flange 25 on adjacent forms lie 25 in close contact with each other and may be provided with openings for the reception of bolts, whereby the adjacent forms may be secured to each other.

Referring to Figure 1, it will be noted that the 30 beam and girder molds cross each other at substantially right angles, and on reference to Figure 2, it will be seen that in the construction illustrated, the girder is of greater vertical depth than the beams. As a result, openings are formed between the ends of the bottoms of the beam forms 35 and the ends of the girder forms. These openings may be closed by means of a substantially U-shaped form 26 of sheet material arranged over the opening between the ends of the girder forms 40 on which it is supported. The side walls of the form 26 engage the inner walls of the adjacent girder forms and continue the same over the openings beneath the bottoms of the adjacent beam forms. If desired, these forms can be secured to angles secured to the ends of the beam forms by bolts or other suitable means.

The outside beam or lintel 6 previously referred to is formed very much like the girder 4, both of which are shown built into the head of the column 50 7. Referring to Figure 2, it will be seen that the lintel comprises an inner wall 27, an outer wall 28, and a bottom wall 29 having downwardly projecting flanges 30 whereby it may be secured to the inner and outer walls in the manner of the 55 beams and girders. The inner wall 27 may be secured to the flange of a T-form 15 adapted to be mounted on the shores 2 with its upper face substantially in the plane of the forms 1. The outer wall rises vertically from the outer edge of 60 the bottom wall to a point where its upper edge is at least as high as the plane of the finished floor, that is, it rises above the inner wall a distance equal at least to the thickness of the floor to be formed. The forms for the lintel may be 65 supported in any suitable manner or directly on the tops of temporary supports or shores 31, as shown in the drawings; or the bottom of the forms may be notched out to fit around the top of the shore and be supported in the brackets in a manner similar to that in which the forms 1 and 15 are mounted, so that the forms may be removed 70 without disturbing the shores on which the con-

crete is supported. The outer wall is anchored against outward movement under the pressure of the concrete by means of flexible cords or wires 32 connected thereto and secured to the inner wall, as usual in the art.

5

It frequently happens that it is desirable to have a space between the adjacent forms 1 which is wider than the standard or unit width of a beam form such as described above. This may occur when a beam opening may be employed to 10 take up the narrow space in the floor, or, when laying a heavy floor on dome forms, it is sometimes desirable to widen the upper part of the beam or girder where the joists form into it. In Figures 5, 6 and 7 is shown a beam form as 15 sembed to fit in such a space, and comprises a narrow rectangular form 35 constructed in all respects like the form 15 except in shape, and has a depending marginal flange. The side of the beam form may be secured to one of its side 20 flanges and a T-shaped form to its other side flange, and the assembled beam form mounted on the shores 2 as previously described.

In Figure 7, a slightly modified form 36 of the T-form is shown having open rectangular openings 37 adjacent its ends to fit and fill the space around three sides of the shore head. Such forms are found convenient in forming a girder into a beam, lintel or column, as will be noted from an inspection of Figure 1. It will be understood that 30 the forms 35 may be made in various widths or adjustable in width to meet various requirements, or that more than one of them may be used on each side of the beam form, or that it may be used on one side of the beam form and omitted 35 from the other side to meet ever-changing conditions.

Although the invention has been described with reference to certain details of construction, it will be understood that this application is intended 40 to cover such changes or modifications as come within the spirit of the invention or scope of the following claims.

I claim:

1. An apparatus for forming concrete floors 45 comprising shores having tops, a plurality of substantially rectangular floor forms constructed of sheet material and adapted to be detachably mounted on said shores in the plane of and around the tops of the shores and in aligned rows arranged substantially perpendicular to each other, and a plurality of beam forms constructed of sheet material and provided with members adapted to be detachably mounted on said shores in the plane of the tops of the shores and of the floor forms 50 and between adjacent rows thereof, said members being formed to fit around the tops of the shores.

55

2. An apparatus for forming concrete floors comprising shores having tops, a plurality of floor forms constructed of sheet material and adapted to be detachably mounted on said shores in the plane of and around the tops of the shores, and a plurality of beam forms adapted to be detachably mounted on said shores between the floor forms and each comprising a pair of members 60 adapted to be detachably mounted on said shores in the plane of the tops of the shores and formed to fit around the tops of said shores, side walls secured to and depending from said members, and a bottom wall arranged between and detach- 65 ably secured to said side walls.

70

HENRY W. ROOS.
